BERNAT MECHLOVITS AND MORRIS BELLOCH, OF NEW YORK, N. Y.

METHOD OF MAKING SWING JOINT DRESS ORNAMENTS

Application filed December 11, 1931. Serial No. 580,240.

This invention relates to new and useful improvements in manufacturing swing joint dress ornaments.

The invention has for an object the construction and manufacturing swing joint dress ornaments which are characterized by the provision of recesses for idle metal in a mould to extend from the frame of the ornament to an inserted wire to form a cross bar. 10 As a further object of this invention it is proposed to arrange the mould in a manner so that the tongue of the ornament extends substantially at right angles to the frame thereof and the idle metal passage extends in 15 the same plane as the frame from one side and around an inserted wire.

A still further object of this invention is the construction of a mould in which the tongue is arranged so that when the dress 20 ornament is formed the tongue need not be passed through the frame but may be used in its formed condition.

A still further object of this invention is the construction of a device of the class described which is of simple durable construction, dependable in use and efficient in operation and which can be manufactured and sold at a reasonable cost. 25

For further comprehension of the invention, and of the objects and advantages thereof, reference will be had to the following description and accompanying drawing, and to the appended claims in which the various novel features of the invention are more particularly set forth. 30

In the accompanying drawing forming a material part of this disclosure:—

Fig. 1 is a perspective view of a mould constructed according to this invention. 40

Fig. 2 is an elevational view looking in the direction of the line 2—2 of Fig. 1.

Fig. 3 is a sectional view as though taken on the line 3—3 of Fig. 2.

Fig. 4 is a view similar to Fig. 3 but illustrating a modified arrangement. 45

Fig. 5 is a view similar to Fig. 2 but illustrating another modified arrangement.

Fig. 6 is a fragmentary view similar to a portion of Fig. 2 but illustrating another 50 embodiment of the invention.

The mould, according to this invention, is composed of three blocks 10, 11 and 12 placed together in a manner so that two of the blocks, namely 10 and 11, are in end contact with each other and both of these in face contact with the third block 12. The faces between the block 12 and the blocks 10 and 11 are recessed at 13 to form the frame of a dress ornament, are recessed at 14 to allow for the extension of a pintle wire through 60 the mould, are recessed at 15 to form an idle metal portion extending from the frame to the pintle portion of the tongue of the ornament, and recessed at 16 to allow the pouring in of metal to reach the frame of the ornament. 65

Screws 18 pass through blocks 10 and 11 for securing these parts together. Pegs 19 project from one of the blocks and engage into corresponding recesses in the other of 70 the blocks so as to insure true alignment. Similarly, pegs 20 project from the blocks 10 and 11 into corresponding recesses in the block 12 to assure proper alignment of these blocks. The wire passage recess 14 is disposed in adjacent corners of the block 12. The ends 21 of this passage are chamfered to allow easy insertion of the wire over which a cross bar will be formed for the tongue of the ornament. As shown in Fig. 3, the ornamented faces of the recesses 13 are disposed within the block 12 and the ornamented faces for the tongue are disposed within the block 10. Consequently, when the ornament which is cased in the mould is taken out the tongue 80 is on the right side ready for use. Recesses 23 are formed in the face of the block 12 in the vicinity of the frame of the ornaments so as to form bearings for a wire inserted within the mould. 85

In Fig. 4 a modified arrangement of the invention has been disclosed in which the recess forming the body of the ornament is disposed within the face of the block 12 and the recess forming the tongue is disposed 90 within the bottom face of the block 11. When an ornament is cased in this mould the tongue thereof will be on the correct side ready for use.

In Fig. 5, another embodiment of the in- 100

vention has been disclosed which is quite similar to the form shown in Fig. 2 but distinguishes merely in the shape of the recess 13' which forms the body of the ornament. It 5 is of substantially crescent shape and terminates in ends 24 which form bearings for the wire inserted and through which holds the tongue. Idler metal recesses 15 extend from the frame recess 13' to the recess 17 which 10 forms the tongue and cross bar portion of the ornament.

In Fig. 6, another arrangement has been disclosed in which a frame recess 13^a is provided of substantially trapezoidal shape. An 15 idle metal recess 15^a extends from the side of the recess 13^a and connects with the tongue recess 17.

In all of the different forms of mould it should be noted that the metal is entered 20 through the top and is discharged into the plane of the frames of the ornaments. From there the metal by reason of the idle metal passage may reach the tongue which is disposed at right angles to the frame and flow 25 along the recess which forms the tongue. This arrangement insures the frame of the ornament to be cast perfectly and any deficiency in the metal flow will occur upon the tongue which usually is partially hidden 30 when the ornament is used.

It is to be understood that shape and size of the idle metal 15 may be varied as desired according the shape and size of the swing joint ornament.

35 While we have shown and described the preferred embodiment of our invention, it is to be understood that we do not limit ourselves to the precise construction herein disclosed and the right is reserved to all changes 40 and modifications coming within the scope of the invention as defined in the appended claims.

Having thus described our invention what we claim as new, and desire to secure by 45 United States Letters Patent is:—

1. A method of casting a swing joint ornament comprising a frame, a cross bar across said frame, and a tongue portion radially on said bar, said method consisting of causing 50 molten metal to flow edgewise of said frame to form said frame, causing some of said molten metal to flow from said frame to said cross bar to form said cross bar, and causing some of said molten metal to flow radially 55 from said cross bar, to form said tongue.

2. A method of casting a swing joint ornament comprising a frame, a cross bar across said frame, and a tongue portion radially on said bar, said method consisting of causing 60 molten metal to flow edgewise of said frame to form said frame, causing some of said molten metal to flow from said frame to said cross bar, causing some of said molten metal to flow radially from said cross bar, to 65 form said tongue, and causing the molten

metal flowing from the frame to said cross bar to travel in a path substantially radial of said cross bar.

In testimony whereof we have affixed our 70 signatures.

BERNAT MECHLOVITS.
MORRIS BELLOCH.
